UNITED STATES PATENT OFFICE.

FRANK FUREDY, OF BROOKLYN, NEW YORK, ASSIGNOR TO BUSHWICK NATIONAL BANK.

ADJUSTABLE WRITING IMPLEMENT.

Application filed July 23, 1924, Serial No. 727,460. Renewed July 16, 1927.

My invention relates to writing implements having adjustable or movable marking elements. While the invention is adaptable in some or all of its features to implements of this class employing pen or stylus points, it is especially adapted, as herein illustrated, to implements of the pencil class in which the marking elements are crayons or leads.

10 An important object of the invention is to provide a pencil in which at least two or any reasonable plurality of crayons or leads are mounted for immediate selective use, with operating mechanism by which either lead 15 may be projected to writing position while the other is withdrawn within the case, and the projected lead may be adjusted to give the desired length of writing point. The general structure or arrangement of the lead 20 holders is substantially similar to that disclosed in my prior application, Serial No. 694,990, filed February 25, 1924, but the present invention embodies important modifications and improvements. Especially, the 25 present invention provides for materially simplifying and reducing the cost of construction by avoiding the necessity for using gears or pinions in the operating mechanism.

30 Another important object is to provide in connection with the lead holders, means for positively ejecting either of the active leads whenever it is desired to do so, as for example, when the lead is almost used up and it is 35 desired to discharge the remaining stub so that a fresh lead may be inserted.

The two leads inserted in the holders and ready for active use by projecting either one at will, may in some cases be of the same 40 color, for instance, black leads of the same grade, and in that case one lead is in reserve for instant use when the other is exhausted, or if of the same color, the leads may be of different grades; otherwise the leads or crayons may be of different colors.

Provision is also made for conveniently carrying a very substantial number of spare leads or crayons within the case.

The characteristics and advantages of the 50 invention are further sufficiently explained in connection with the following detail description of the accompanying drawings, which show exemplifying embodiments of the invention. After considering these examples, persons skilled in the art will understand that many variations may be made

within the principles of the invention, and I contemplate the employment of any structures that are properly within the scope of the appended claims.

Fig. 1 is a longitudinal section, enlarged, of a pencil structure embodying the invention in one form.

Fig. 2 is a section at 2-2, Fig. 1.

Fig. 3 is a section at 3-3, Fig. 1.

Fig. 4 is a section at 4-4, Fig. 1.

Fig. 5 is a side elevation on reduced scale of the main lead shifting or impelling member.

Fig. 6 is a longitudinal section of a guide 70 member which serves mainly to direct the leads in a lateral shifting or pivotal movement.

Fig. 7 is a side elevation of the complete pencil.

Fig. 8 is an enlarged fragmentary detail showing mainly the lead holder and ejector.

Fig. 9 is a longitudinal section of the upper portion of a modified structure.

Fig. 10 is a transverse section at 10-10, 80 Fig. 9.

Figs. 11 and 12 are detail views of the modified structure.

In the physical embodiment of the invention as illustrated in Figs. 1 to 8 inclusive, 1 85 is a tubular case or housing in which is located a tubular guide structure 2, Fig. 6. Throughout the greater part of its length this guide structure is spaced away from the case. The lower portion of the guide member 2 is split or divided into two members 3 and 4 separated by oppositely located longitudinal slots 5. The lower ends of the members 3 and 4 are flared out and provided with externally threaded segments 6. The 90 upper portions of the members 6 are secured within the lower end of the case, as clearly shown in Fig. 1, by soldering or brazing or otherwise, to secure the guide member 2 against rotation or end movement in relation 95 to the case. The threaded portions 6 project beyond the end of the case, and the generally conical tip 8 is screwed upon these portions. The tip may therefore be removed when necessary, although it is usually unnecessary to move the tip in the ordinary use of the pencil.

A tubular member 10, Fig. 5, which may conveniently be designated as a shifter or lead impeller, is rotatively located between 110 the guide member 2 and the case 1. The lower end of the impeller rests on shoulders

11 formed just above the threaded portions 6 of the guide member. A shallow annular channel 12 is formed near the upper end of the impeller and after the latter is placed 5 in the case, the upper edge of the case is pressed or "spun" inward to form a bead 13 having a bearing fit in the channel 12 to secure the impeller and other parts 10 against outward displacement and at the same time permit rotation of the impeller. Above channel 12 the impeller has a cylindrical portion 15 on which a cap 14 is placed 15 with a tight sliding fit. The engaging faces of the cap and cylindrical portion 15 may be roughened or knurled if necessary to insure rotation of the impeller when the cap is turned. The cap conveniently provides 20 for enclosing an eraser 16 which may be inserted directly in the cylindrical extension 15 of the impeller, or otherwise, as shown, the eraser may be placed in a holder or thimble 17 screw threaded to engage with in the cylindrical impeller portion 15 so that the eraser with its holder may be easily 25 removed and replaced by a new one if desired. To impart a distinctive and decorative appearance to the pencil, the cap 14 desirably terminates in an end plate 18 which is inclined in relation to the pencil 30 axis and the periphery of this end plate is in the form of a slightly projecting flange or bead 19. This facilitates removal of the cap.

The guide member 2 is formed with two opposite longitudinal substantially semi-cylindrical channels 20 to accommodate stems 35 21 and 22 which carry the active leads. Along the inward portion of each guide channel is a guide slot or cam track 23. Each of these tracks consists of a straight 40 upper portion 23^a and a straight lower portion 23^b, these portions being connected by a short angularly arranged track portion 23^c to produce a pivotal or rotative movement of the lead holder stem in co-operation with 45 projections thereon as later explained. Stem 21 has a laterally extending knob or cam follower 24 located in the corresponding cam track 23, and stem 22 has a similar projection or cam follower 25 located in its corresponding track 23.

The impeller 10 has on its upper portion an impeller slot 27 in the form of a helix, which includes a portion 28 of relatively steep pitch and an upper portion 29 of relatively fine pitch. In the lower portion of the impeller is an impeller slot 30, similar to the slot 27, except that its lead is in the opposite direction, that is the lead of the slot 27 corresponds to a left hand screw 55 thread and that of slot 30 corresponds to a right hand thread. The slot 30 in similarity to slot 27 has a relatively long portion 31 of relative steep pitch and a short upper portion 32 of relatively fine pitch. The two 60 impeller channels or slots are arranged in

different longitudinal portions of the impeller since it is usually desirable or convenient for manufacturing reasons to cut these slots entirely through the tubular wall and therefore they must be located on different longitudinal portions of the impeller tube. 70

Stem 21 has an outwardly extending projection or impeller track follower 34 located in impeller slot 27 and stem 22 has a similar outward projection or track follower 33 located in impeller slot 30. To correspond with the locations of the respective slots, projection 24 of stem 21 is located substantially at its upper end and projection 33 of 80 stem 22 is located relatively near the lower end of the stem.

The main portion of each of the stems 21 and 22 is straight, but at the lower end each stem is formed with a cranked portion 40 terminating in a short straight portion 41, the cranked portion being so designed that the lower straight portion of the stem is in line with the center axis of the case when the stem is in one of its rotative 85 positions. A lead grip 45 is placed on the lower end of each stem. The lower portion of the grip is provided with opposite slots 40 forming two semi-cylindrical members which resiliently grip the lead when 90 it is pushed between them. 95

To provide for conveniently and positively ejecting the lead ends or stubs, the grip is preferably mounted for sliding movement upon the lower stem end. For this purpose 100 a portion 46 of the lower straight end of each stem is made of reduced diameter, this reduced portion terminating in shoulders 47 and 48. After the grip is placed upon the lower end of the stem its upper tubular portion 49 is spun or pressed inward to have a sliding fit on reduced stem portion 46, and in this operation a shoulder 50 is formed at the lower end of the impressed sleeve portion 49 to co-operate with shoulder 48 and prevent downward dislocation of the lead grip. 105 To co-operate with the slideable lead grip, a clutch is provided which consists of a tubular member or thimble 55 of thin resilient sheet metal secured within the tip 8. The lower portion of the thimble 55 is slotted to provide separate resilient fingers 56 terminating in rounded ends 57 adapted to co-operate with the lead grip and especially 110 with the outward portion of the shoulder 50 thereon, as explained below. 115

The slots or longitudinal openings 5 formed between the lower members 3 and 4 of the guide structure 2 provide lateral guides for the stems 21 and 22 when they 120 are in their lower positions. Desirably one edge of each of the members 3 and 4 along the corresponding slot 5 is pressed or bent inward to form a bead 60 which co-operates 125 with the cranked member 40 of the corre- 130

sponding stem at a point adjacent the long straight stem shank, and forms a stop to limit the pivotal movement of the stem when the lower stem end is brought into the central or axial position, as clearly shown in Fig. 3.

The described construction and arrangement provide conveniently for a large central chamber 65 within the guide 2, in which 10 a large number of spare leads of different grades, qualities or colors may be placed. The lower end of the upper portion of the guide constituting the chamber 65 is closed by an end plate 66. The upper end of the 15 chamber may remain open so that access may be had to the spare leads by removing cap 14 and the eraser 16 or its holder 17.

Fig. 1 shows one stem 21 in fully retracted position and the other stem 22 in full 20 projected or downward position. In the movement of stem 22 to the position shown, its lead grip 45 passes between the spring fingers 56 of the clutch 55 and the outer end of the grip then encounters a shallow 25 shoulder 8^a formed in the tip at the inward end of its end bore, which closely fits the lead and the stem end. Further movement of the stem then causes the lower stem end to move outwardly from the position shown 30 in Fig. 8 through the tubular end of the lead grip to positively discharge the short lead stub L¹ from the grip. To load the pencil or to insert a fresh lead in grip 45 it is only necessary to retract stem 22 (or the other stem 35 when it is in a corresponding position) slightly until the outer end of the stem is withdrawn to the position shown in Fig. 8, with shoulder 48 in engagement with shoulder 50 of grip 45. The outer periphery of 40 shoulder 50 is still engaged by the curved ends of the clutch fingers 56. The new lead is then inserted through the bore in the end of the tip and into the grip sleeve 45. The stem is then retracted further, whereupon 45 the grip sleeve 45 moves along with the stem, shoulder 50 passing upwardly between the clutch fingers 56 which yield outward to permit this passage. In the further inward movement of the stem, the clutch fingers approximately fit the lead and tend to steady 50 and guide it until the outward end of the lead passes above the fingers.

The stem movements are accomplished by 55 rotating cap 14 or the upper end of impeller sleeve 10 in one direction or the other. In the manner shown, sleeve 10 is turned in a right-hand direction. Impeller slot 30 then acts on stem projection 33 to move stem 22 inward while slot 27 acts on projection 34 60 to move stem 21 outward or downward. During this time the cranked portion 40 of stem 21 is in an angular or non-radial position as shown in Fig. 2, so that the lead grip and lead carried by stem 21 are located 65 toward one side of the lower central cham-

ber of the pencil, and the cranked portion of stem 22 is in a radial position, as also shown in Figs. 2 and 3, with the lead grip and lead aligned with the tip bore and the central axis of the pencil. When the described movement has continued until the lead grips are nearly opposite, or until members 24 of stem 21 approaches the upper end of the angular portion 23^c of the corresponding guide slot 23, and member 25 of 70 stem 22 approaches the lower end of the corresponding angular guide slot portion, the members 24 and 25 then pass respectively downward and upward through said angular guide slot portions, which rotate the 75 respective stems somewhat less than a quarter-turn, to reverse the angular positions of the crank stem members; or in other words, to bring the lead of stem 21 to central position while the grip and lead of stem 22 80 are moved toward one side of the central chamber. Further continued rotation of the cap in the same direction then causes lead L carried by stem 21, to be projected from 85 the tip for use.

While the pitch-angle of the impeller slots could be made uniform in some cases, such an arrangement would tend to increase the length of the pencil for a certain total amount of longitudinal lead travel. To keep the length of the pencil as small as possible within reasonable limits, therefore, it is usually preferable to make a short portion, such as the portions 29 and 32, of each impeller slot, of relatively fine pitch. Therefore, when one lead is nearly fully projected or its grip is in nearly lowermost position, the other lead and its stem have relatively small longitudinal travel by reason of the corresponding projections 34 or 33, being 90 located in the slot portions 29 or 32. The angular guide slot portions 23^c may be so located with respect to the impeller slots that the "switching" or pivotal movement of the stem will occur while at least one of 95 them is in the lower portion of one of the fine-pitch slot sections, or while both of the projections 33 and 34 are in an upper part of the coarse-pitch sections 31 and 28 respectively.

When either lead is in projected position, it may be adjusted for the desired length of writing point by appropriate rotation of cap 14. The complete retraction of either lead and the projection of the other and adjustment of it for proper writing length is effected almost automatically and practically instantly, after the pencil has been manipulated only once or twice by the ordinary user. The ejection of a lead or lead stub 100 is also practically automatic, since when a lead is nearly used up and becomes shorter and shorter it will naturally be projected more and more, until finally the lead grip is 105 brought down to lowermost position, as 110

shown in Fig. 1, and the lead stub is then ejected in the manner previously described.

Figs. 9 to 12 show a modification in which the impeller 10^a is in the form of a centrally-located cylinder having impeller grooves 27^a and 30^a which cross each other at diametrically opposite faces of the cylinder. These grooves may have lower portions of coarse pitch and upper portions of fine pitch, 10 as in the case of the slots of impeller 10. The upper end of the cylinder is formed of a squared head 70 detachably engaged by a squared socket 71 formed on the lower end of a hollow knob 72 which is provided with 15 a groove 13 as in the case of the upper end of the impeller tube of Fig. 1 to co-operate with a bead 12 formed in the upper end of case 1. To facilitate removal and replacement of the knob 72 the upper end of the 20 tube is desirably provided with longitudinal slots 74 so that the knob groove 13 may be easily snapped into and out of engagement with the segments of the casing bead 12. An eraser 16^a may be fitted into the hollow 25 knob and a cap 75 is detachably fitted over the outer end of the knob to conceal the eraser.

The lower end of the impeller is rotatably mounted in a plate 76 located at the lower 30 ends of guide members 77 which are of substantially semi-cylindrical form and located oppositely against the inward wall of the case, Fig. 10. Plate 76 is arranged to fit and locate the lower ends of these guide 35 members. The impeller cylinder may be further located and guided in central portions of plates 78, which are of approximately semi-cylindrical form. These plates also have edges engaging against narrow flanges 40 formed on the guide members 77 to hold the latter in position. Guide slots 82 are formed in inward portions of the guide members. To cooperate with the described 45 impeller and guide slot arrangements of the respective lead stems 21 and 22, each has a single projection 23 at its lower end, this projection being arranged to pass through the corresponding guide slot 82 and engage in the corresponding impeller channel 27^a or 50 30^a. The guide slots have angular portions similar to the portions 23^a previously described and by rotating the impeller cylinder the stems are moved for the projection or retraction of either lead and its adjustment in a manner substantially similar to 55 that described in connection with Figs. 1 to 8.

If in any case the projections 23 do not properly follow the impeller channels or 60 tend to be diverted from the proper course where these channels intersect, followers 84 may be provided, which are pivotally mounted on the stem projections, these followers having tapered or rounded ends and being 65 long enough to insure the proper following

of one of the impeller channels. One of the followers 84 is shown in Fig. 11 in position in its corresponding channel 27^a at the intersection of the latter with channel 30^a, showing clearly the manner in which the 70 follower pursues its course through the proper channel while crossing the other one.

Spare leads may be located in either of the chambers 86, provided between side plates 78 and the casing wall, and access may be 75 had to them by removing the knob 72.

For a given lead travel the pencil constructed in accordance with Figs. 9 to 12 may in some cases be made substantially shorter than in the other construction, for 80 the reason that the two impeller channels occupy substantially the same longitudinal portion of the impeller body. The construction as shown in Figs. 1 to 8 may, however, be employed in a pencil which gives 85 the desired amount of lead travel and is no longer than ordinary or known types of adjustable pencils.

I claim:

1. An adjustable pencil comprising a case, 90 a plurality of lead stems arranged therein for longitudinal and pivotal movement, a rotary impeller in the case having helical channels, the lead stems having members co-operating with the respective channels for 95 longitudinal stem movement, and guide channels located longitudinally in the case and having angular portions and co-operating with members of the lead stems to move them pivotally at a certain point in their 100 longitudinal travel, the stems being moved simultaneously in opposite directions and partly rotated to selectively project and retract the different leads, by rotation of the 105 impeller.

2. An adjustable pencil comprising a case, 110 a plurality of lead stems arranged therein for longitudinal and pivotal movement, a rotary impeller in the case having helical channels, the lead stems having members co-operating with the respective channels for simultaneous movement of different stems in 115 opposite directions, and guide channels located longitudinally in the case and having angular portions and co-operating with members of the lead stems to move them pivotally at a certain point in their longitudinal travel, the guide channels being located in a generally tubular guide structure 120 located in an upward part of the casing and within the impeller.

3. An adjustable pencil comprising a case, 125 a plurality of lead stems arranged therein for longitudinal and pivotal movement, a rotary tubular impeller in the casing having lateral projections cooperating with the respective channels for simultaneous movement of different stems in opposite directions, and guide channels located longitudinally in the 130

case and having diagonal portions and co-operating with members of the lead stems to move them pivotally at a certain point in their longitudinal travel.

- 5 4. An adjustable pencil comprising a case, a plurality of lead stems arranged therein for longitudinal and pivotal movement, a rotary tubular impeller in the case having helical channels, the lead stems having lateral projections co-operating with the respective channels for simultaneous movement of different stems in opposite directions, and guide channels located longitudinally in the case and having diagonal portions and co-operating with members of the lead stems to move them pivotally at a certain point in their longitudinal travel, the guide channels being located in a generally tubular guide structure located in an upward part of the casing and within the impeller, said guide structure having lower extensions non-rotatively secured to the case.

5. An adjustable pencil comprising a tubular case, a tubular impeller rotatively mounted therein and provided with a helical channel, a guide structure located within the impeller and non-rotatively secured in the case, the guide structure also having a generally-longitudinal guide channel including a diagonal portion, and a cranked lead stem mounted for longitudinal and pivotal movement in the guide structure and having a member engaging with the impeller and guide channels to produce longitudinal and pivotal movement of the stem by rotation of the impeller, the guide structure also having a lower longitudinal slot to guide the stem in its lower positions.

6. An adjustable pencil comprising a tubular case, a tubular impeller rotatively mounted therein and provided with a helical channel, a guide structure located within the impeller and non-rotatively secured in the case, the guide structure also having a generally-longitudinal guide channel including a diagonal portion, and a cranked lead stem mounted for longitudinal and pivotal movement in the guide structure and having a member engaging with the impeller and guide channels to produce longitudinal and pivotal movement of the stem by rotation of the impeller, the guide structure also having a lower longitudinal slot to guide the stem in its lower positions, the slot having a flange to limit pivotal movement of the stem by co-operation with its cranked portion.

7. An adjustable pencil comprising a tubular case, a tubular impeller rotatively mounted therein and provided with a plurality of helical channels, a guide structure located within the impeller and having members engaging the case and also having longitudinal guide channels each including a diagonal portion, and a plurality of cranked lead stems mounted for longitudinal and piv-

otal movement in the guide structure, the stems having members engaging with the impeller channels and the guide channels to produce longitudinal and pivotal movement of the stems by rotation of the impeller.

8. An adjustable pencil comprising a tubular case, a tubular impeller rotatively mounted therein and provided with a plurality of helical channels, a guide structure located within the impeller and having members engaging the case and also having longitudinal guide channels each including a diagonal portion, and a plurality of cranked lead stems mounted for longitudinal and pivotal movement in the guide structure, the stems having members engaging with the impeller channels and the guide channels to produce longitudinal and pivotal movement of the stems by rotation of the impeller, the guide structure also having lower longitudinal slots to guide the stems in their lower positions.

9. An adjustable pencil comprising a tubular case, a tubular impeller rotatively mounted therein and provided with a plurality of helical channels, a guide structure located within the impeller and having members engaging the case, the guide channel including a diagonal portion and a plurality of cranked lead stems mounted for longitudinal and pivotal movement in the guide structure, the stems having members engaging with the impeller channels and the guide channels to produce longitudinal and pivotal movement of the stems by rotation of the impeller, the guide structure also having lower longitudinal slots to guide the stems in their lower positions, the slots having flanges to limit pivotal movement of the stems by co-operation with their cranked portions.

10. A pencil comprising a case, a lead stem mounted therein for longitudinal and pivotal movement and having a cranked portion, and a relatively movable lead grip at the lower end thereof, the casing tip having a central bore to guide the projected lead, and guide means within the tip co-operating with the lead and lead grip to support and guide the lead and also to operate the grip.

11. A pencil comprising a case, a lead stem mounted therein for longitudinal and pivotal movement and having a cranked portion, a lead grip mounted for limited reciprocating movement on the stem, and a clutch comprising flexible means located within the case near its lower end and adapted to co-operate with the lead grip to return the grip to normal position after it has been retracted on the stem in a lead-ejecting action.

12. A pencil comprising a case having a tip, a plurality of lead stems mounted therein for longitudinal and pivotal movement, each stem having a cranked portion, a lead grip mounted for limited reciprocating

movement on each stem below said cranked portion, and a clutch comprising flexible fingers located within the case near its lower end adapted to co-operate with the lead 5 grips to return them to normal position after ejecting actions.

13. A pencil structure comprising a case, a lead stem therein arranged for reciprocating and pivotal movement and having a portion of reduced diameter, a lead grip mounted for reciprocating movement on the lower end of the stem and having a portion fitting the reduced stem portion, the lower end of the case having a tip provided with a lead 10 bore and an interior shoulder to co-operate with the end of the lead grip, and a clutch including yieldable fingers adapted to permit passage of the lead grip and to co-operate with a shoulder thereon to return the 15 grip to normal position on the stem after a lead-ejecting action.

14. A pencil structure comprising a case, a lead stem therein arranged for reciprocating and pivotal movement and having a cranked lower end, said end having a portion of reduced diameter, a lead grip mounted for reciprocating movement on the lower end of the stem and having a portion fitting the reduced stem portion, the lower end of the case having a tip provided with a lead 25 bore and an interior shoulder to co-operate with the end of the lead grip, and a clutch including yieldable fingers adapted to permit passage of the lead grip and to co-operate with a shoulder thereon to return the 30 grip to normal position on the stem after a lead-ejecting action.

Signed at New York city in the county of New York and State of New York this 18th day of July A. D. 1924.

FRANK FUREDY.
